Alfred Muller, 3 Avenue des Myrtilles,
67530 Ottrott, Bas-Rhin, France

Filed Nov. 4, 1974, Ser. No. 520,940

Claims priority, application France May 7, 1974

Term of patent 14 years

Int. Cl. D10—04

U.S. Cl. D10—69

FIG. 4

FIG. 1

FIG. 2

FIG. 3

FIG. 5

FIG. 6

FIG. 6

FIG. 1 is a front elevational view of a spirit level showing my new design;

FIG. 2 is a top plan view thereof;

FIG. 3 is a rear elevational view thereof;

FIG. 4 is a right end elevational view thereof;

FIG. 5 is a left end elevational view thereof; and

FIG. 6 is a bottom plan view thereof.

I claim:

The ornamental design for a spirit level, substantially as shown and described.
